ELECTRICALLY HEATED NECKTIE PRESS

Irving A. Lake, Mount Vernon, N. Y.

Application October 16, 1931, Serial No. 569,180

6 Claims. (Cl. 219—19)

This invention relates to electrically heated necktie presses or restorers, and has for its object certain improvements in electrically heated necktie presses or restorers.

Various devices have been placed on the market with which to take creases out of neckties and the like. These have for the most part consisted of flat unitary sheet metal tongues or bent wires adapted to fit inside a necktie. In this practice, 10 the device actually consists of a frame over which the creased tie may be tightly stretched. It is not uncommon practice to moisten the tie and then to let it dry over the inserted frame. As a result of this procedure, the creases are removed. This wetting and drying procedure consumes considerable time, and the practice has not been found satisfactory.

It has also been proposed to construct necktie presses or restorers that are electrically heated. 20 That is to say, the press or restorer is provided with an extended electric resistance element, the terminals of which contact with or are connected to leads of insulated current-carrying wires connecting with a source of electric current. Trou- 25 ble has been experienced in designing the electric resistance element so that it will not contact with metal and thus establish a short circuit. This means that the resistance element itself may contact at points to establish an un- 30 desirable short circuit, or the resistance element, when mounted in a metallic covering, may contact with metal of the covering.

The present invention relates to improvements in electrically heated necktie presses or restorers 35 that are adapted to avoid for the most part the difficulties heretofore encountered in the manufacture of such devices. A construction is contemplated that permits the manufacture of the presses or restorers economically and in a man- 40 ner to avoid short circuits.

According to the present invention, an electrically heated necktie press or restorer is contemplated that comprises a combination of an electric resistance element mounted loosely within 45 folds of heat-resistant sheet-material extending lengthwise of the interior of the press; the folds of the heat-resistant sheet-material covering the resistance element to keep it out of contact with outside metal, and with itself.

The present preferred embodiment of the invention consists of a tongue-like outer covering, 50 housing or sheathing, which may advantageously consist of thin sheet metal, such as aluminum, provided with a hollow interior adapted to receive and hold the resistance element mounted

in the unique manner particularly contemplated. The resistance element advantageously consists of a finely coiled wire mounted loosely within folds of the heat-resistant sheet-material extending lengthwise of the interior of the press. It 60 is preferably stretched around the extreme end of the heat-resistant sheet-material, so that the ends of the resistance wire are located at the other end of the sheet material; where they are attached in electrical contact with the ends of 65 insulated wires adapted to be connected with a source of electric current supply. The far ends of these wires are preferably attached to a plug that may be inserted in a current supply socket.

The heat-resistant sheet-material is of a size 70 preferably adapted to fit substantially snugly within the press. The sheet-material may consist of a single sheet, the opposite side portions of which are provided with reversed folds to give three thicknesses of material. In this practice, 75 the inside edges of the folded portions are advantageously disposed immediately adjacent one another; either contacting with or spaced from one another, as desired. The outer edges of the folded portions may be disposed at substantially 80 the same distance from the longitudinal center of the sheet. All of the lines of fold may be substantially adjacent to one another.

In the present preferred practice, registering 85 slots or slits are provided in or near lines of fold at the upper and lower ends of the sheet to give a recessed support for the electric resistance element, to keep the element out of contact with outside metal.

In another specific application of the invention 90 the heat-resistant material may consist of two sheets, the sheets being superposed to form a double thickness; and the sheets being attached to one another along their longitudinal centers. In this construction, the pair of superimposed insulation sheets may be connected along their longitudinal centers; the top sheet being narrower than the bottom one, if desired, better to fit within in the outer casing of the press.

The outer metal casing, housing, sheathing or tongue advantageously comprises a lower flat sheet, while the upper sheet is arched; as more particularly shown in the attached drawing. These two sheets are complementary to one another, and the outer edges of the lower sheet are so bent-over in relation to the outer edges of the upper sheet that they are permanently joined and secured to one another; while giving substantially smooth surfaces. As pointed out above, these 100 105 110

joined metal sheets advantageously form a tongue adapted to fit into a necktie, such as a four-inch. The upper end of the tongue terminates in a relatively narrow portion, while the lower end of the tongue is broader, to conform with the broader lower ends of neckties.

A handle is preferably permanently attached to the lower end of the tongue. This handle may consist of stamped fiber sheet material curved to conform to a convenient hand grip. Two such stamped fiber sheets are complementarily joined to one another, but with a space between them adapted for the support and maintenance of the insulated wires that connect with the electric resistance element confined within the folds of the heat-resistant sheet-material; which sheet-material is in turn supported within the hollow interior of the tongue portion of the press.

The present invention will undoubtedly be better understood if reference is made to the accompanying drawing, taken in conjunction with the following description, in which:

Fig. 1 shows a full length plan view, partly in section, of an assembled electrically heated necktie press or restorer illustrative of a practice of the invention;

Fig. 2 is a longitudinal cross-section on the line 2—2 of Fig. 1;

Fig. 3 is a transverse cross-section on the line 3—3 of Fig. 1, showing the interior construction of a preferred embodiment of the invention;

Fig. 4 is a view in perspective, and partly in section, of a preferred form of heat-resistant sheet-material; in which is loosely mounted a heat resistant element;

Fig. 5 is a transverse section of the heat-resistant sheet-material more particularly shown in Figs. 3 and 4;

Fig. 6 is a plan view in part of an un-bent section of the heat-resistant sheet-material shown in Figs. 1 to 5.

Fig. 7 is a modified form of the heat-resistant sheet-material construction, in which the folded portions contact along adjacent folds; but in which the folded portions are narrower than the main body portion;

Fig. 8 is another modified form of the same general type of heat-resistant sheet-material construction, but in which the folds are spaced from one another; and

Fig. 9 shows another specific form of heat-resistant sheet-material construction, consisting of a pair of superposed heat resistant sheets attached to one another along their longitudinal centers.

The electrically heated necktie press or restorer shown comprises a tongue 10, preferably tapered, as indicated, and to which is attached a handle 11. Insulated electric wires 12 extend lengthwise through the longitudinal center of the handle and are attached at their ends with a coiled heat resistance element 13 loosely supported or mounted within the folds of a heat-resistant sheet-material 14.

The tapered tongue portion comprises a lower smooth flat sheet metal element 15, the outer edges 16 of which are bent over to receive the outer edges 17 of an arched upper sheet metal element 18. The sheet metal employed advantageously consists of thin aluminum, or other suitable sheet metal. A metal should be selected that is substantially rust-proof and which may be made to retain a substantially smooth outer surface. As more particularly shown in Fig. 3, the

lower and upper sheets are permanently attached to one another by bending the outer edges 16 around the outer edges 17. Due to the arched nature of the upper sheet 18 a hollow interior 19 is provided within the tongue, in which to insert the electric resistance element and its mounting.

The heat-resistant sheet-material element 13 extends lengthwise of the interior of the hollow portion of the tongue. This heat-resistant sheet-material, referring for the moment to Fig. 5, consists of a single sheet comprising a lower body portion 20. Opposite side portions of the sheet are provided with reversed folds 21 and 22; 23 and 24, respectively, to give three thicknesses of material. The inside edges 25 and 26 of the folded portions are disposed immediately adjacent to one another. Spaces 27 and 28, respectively, are provided on the inside of the folded portions, adapted to receive the heat resistance element 13.

If reference is now made to Fig. 4, it will be seen that the heat resistance element 13 is mounted loosely within the folds of the heat-resistant sheet-material. The approximate central portion of the resistant element fits through a slotted or recessed portion 29. It will be seen that this slotted portion consists of registering slots or slits provided in or near adjacent lines of fold at each end of the sheet to give a recessed support for the electric resistance element and to keep the same out of contact with outside metal. The slits or slots are provided by cutting the sheet within what will be the second thickness of the finished mounting; as indicated by the heavy line *a* in Fig. 6. This practice makes for two opposing flaps *b* and *c* that fit under one another to form a ship-lap joint that will completely cover the electric resistance coil when mounted in its proper position.

The electric resistance element and its protective covering are shown in positions within the tongue, in Fig. 1. It will be noticed that the upper end of the heat-resistant sheet-material contacts with the sides of the interior of the tongue. While this is not absolutely necessary, such a construction tends to keep the electric resistance element and its mounting in a fixed position. The ends of the heat resistance element connect with the ends of the insulated wires 12. Due to the rigidity offered by the insulated wires, held in position in the handle portion 11, the lower end of the heat-resistant sheet-material element is kept in a substantially fixed position. Inspection of Fig. 3 will show how the folds of the heat-resistant sheet-material encompass the electric resistance wire coil, to keep the coil out of contact with the metal elements of the tongue and to keep the coil out of contact with itself. It will also be noticed that when the coil is mounted within the folds, that the fold portions tend to contact with the inside faces of the tongue. This construction helps to give rigidity to the entire interior mounting, while at the same time offering the desired protection against short circuits.

The handle portion 11 advantageously consists of two stamped or cut and superposed sheet fiber handle portions 30 and 31, so separated from one another as to provide a space 32 adapted to receive and retain the insulated wires 12. These superposed handle portions are preferably riveted to the lower end of the tongue 10 by means of countersunk rivets 33. The lower ends of the handle portions are likewise preferably riveted together by countersunk rivets 34.

Figs. 7, 8 and 9 illustrate various modifications

of practices of the invention involving mountings for the electric resistance element. In the case of the mountings shown in Fig. 7, the upper folds 35 and 36, respectively, do not extend to the side edges of the lower body portion 27. The construction shown is otherwise essentially the same as that shown in Fig. 5.

In the case of the mounting shown in Fig. 8, the upper fold portions are separated by a space 37. The upper fold portions may or may not, as desired, be made to extend to the outside edges of the lower body portion.

The mounting shown in Fig. 9 is to be distinguished from that shown in Figs. 5, 7 and 8 in that two superposed sheets are employed, the sheets being attached to one another approximately along their longitudinal centers. The construction shown comprises a lower sheet 38 and a superposed upper sheet 39. In one specific application of the invention, the lower sheet 38 is broader than the upper sheet 39. Spaces are of course provided between the sidefolds of the sheets for mounting the electric resistance element loosely. The pair of superposed sheets may be attached to one another in any convenient manner. For example, the sheets may be sewed to one another along their longitudinal centers by means of threads 40. The means employed to attach the superposed sheets should be such as to resist disintegration when the electric resistance element is heated. If the means for attaching the sheet, such as threads, become disintegrated, the electric resistance element will come together; which is to be avoided.

While I have described several specific embodiments of the invention, it will of course be understood that certain variations are possible; all of which may well fall within the spirit of the present invention and the principles herein disclosed.

I claim:

1. In an electrically heated necktie press, the combination of a casing, a single elongated sheet of heat-resistant material extending lengthwise of the casing, said sheet having opposite side portions provided with longitudinally extending reversed folds forming at least three thicknesses of material, and an electric resistance element loosely mounted between folds of said sheet material, said sheet material having registering slots provided in adjacent lines of fold at one end of the sheet to give a recess support for the electric resistance element and to keep the element out of contact with outside metal.
2. In an electrically heated necktie press, the combination of an elongated casing having a part thereof of generally outwardly-convex formation in transverse cross section, layers of elongated heat-resistant sheet material extending lengthwise of the interior of the casing and underlying at least a part of the convex portion, said layers being spaced from one another and arranged to form at least two generally U-shaped channels, said channels being positioned with their closed ends closest to one another, and an electric resistance element between the folds of the heat-resistant sheet material and covered thereby, the combined thickness of the heat-resistant sheet

material and the electric resistance element being sufficiently great that the free ends of the sheet material defining the U-shaped channels are forced towards each other by the convex portion of the casing to cause said ends of the sheet material to at least partially enclose the electric resistance element.

3. In an electrically heated necktie press, the combination of an elongated casing having a part thereof of generally outwardly-convex formation in transverse cross section, a single sheet of heat-resistant sheet material extending lengthwise of the casing and having opposite side portions reversely folded to form at least three folds of material with at least two folds of the material being spaced to form channels, said folded sheet material at least in part underlying the convex portion of the casing, an electric heat resistance element mounted loosely in said channels, the combined thickness of the heat-resistant sheet material and the electric resistance element being sufficiently great that the ends of the folds defining the channels are forced toward each other by the convex portions of the casing to at least partially enclose the electric resistance element.

4. In an electrically heated necktie press, the combination of a casing, a single sheet of heat-resistant material extending lengthwise of the casing, said sheet having opposite side portions each provided with longitudinally-extending reversed folds so that the material is twice doubled back upon itself to form at least three thicknesses of material, one fold of each side portion extending outwardly and being unattached to adjacent folds except along its fold line, and an electric resistance element loosely mounted between said last-mentioned folds and next adjacent folds.

5. In an electrically heated necktie press, the combination of a casing, a single sheet of heat-resistant material extending lengthwise of the casing, said sheet having opposite side portions each provided with longitudinally-extending reversed folds so that the material is twice doubled back upon itself to form at least three thicknesses of material, one fold of each side portion extending outwardly and being unattached to adjacent folds except along its fold line, and an electric resistance element loosely mounted between said last-mentioned folds and next adjacent folds, the inside edges of the folded portions being disposed adjacent one another.

6. In an electrically heated necktie press, the combination of a casing, a single sheet of heat-resistant material extending lengthwise of the casing, said sheet having opposite side portions each provided with longitudinally-extending reversed folds so that the material is twice doubled back upon itself to form at least three thicknesses of material, one fold of each side portion extending outwardly and being unattached to adjacent folds except along its fold line, and an electric resistance element loosely mounted between said last-mentioned folds and next adjacent folds, the outer edges of the folded portion being disposed at substantially the same distance from the longitudinal center of the sheet.

IRVING A. LAKE.
